UNITED STATES PATENT OFFICE.

JAMES T. COWLEY, OF LOWELL, MASSACHUSETTS, ASSIGNOR TO THE LAMSON CONSOLIDATED STORE SERVICE COMPANY, OF NEWARK, NEW JERSEY.

CONVEYING APPARATUS.

SPECIFICATION forming part of Letters Patent No. 608,579, dated August 9, 1898.

Application filed February 17, 1898. Serial No. 670,621. (No model.)

To all whom it may concern:

Be it known that I, JAMES T. COWLEY, of Lowell, in the county of Middlesex and State of Massachusetts, have invented certain new and useful Improvements in Conveying Apparatus, of which the following is a specification.

My invention relates to improvements in conveying apparatus, and especially to the class of conveying apparatus known as "cable carriers," and it has for its object to provide means on the several tracks converging at the terminal station whereby carriers belonging to a certain track can engage only the propelling-cable of said track when placed thereon at the terminal station and be propelled to the station to which they belong.

My invention consists of certain novel features hereinafter described, and particularly pointed out in the claims.

In the accompanying drawings, which illustrate a construction embodying my invention, Figure 1 represents a side view in perspective of a line composed of an upper and a lower track entering the terminal station and representing a carrier placed upon the upper return-track and moved forward toward the mechanism which operates the gripping mechanism on the carrier to grip the cable.

Fig. 2 is a side view in perspective of part of the apparatus shown in Fig. 1 and showing the carrier moved beyond the position shown in Fig. 1, with the gripping mechanism around the cable preparatory to gripping the same.

Fig. 3 is a side view in perspective and looking at the front end of the carrier and showing the position of the parts the same as shown in Fig. 2, with the gripping mechanism about to grip the cable. Fig. 4 is a plan view of the carrier. Fig. 5 is a side view in perspective taken from the opposite side from that shown in Fig. 1, with the carrier on the upper return-track and moved forward toward the mechanism for actuating the gripping mechanism to grip the cable.

Fig. 6 is a side view in perspective taken on the opposite side from that shown in Fig. 5 and illustrating the carrier in a position beyond that shown in Fig. 5, with the grip closed and the cable below the grip.

Like letters of reference refer to like parts throughout the several views.

The two opposite rails A' of the return-track A are supported and firmly secured to the standard B⁶. Near said standard B⁶ the rails are spread out of a straight line to form an opening A², at which point the carrier is applied to the return-track A. The carrier C is adapted to engage with the cable D, running over the pulleys E, mounted in the lugs E' on said standard B⁶ and connected to and driven by suitable driving mechanism. The carrier C is provided with a cover C', held in a closed position by a suitable spring-catch, which is adapted to be operated by a push-button C² to release the cover C', and the spring C³ will throw up the cover C' and open the interior of the carrier.

F represents suitable switch pins or lugs on the carriers by which the carriers are switched at their respective stations. These lugs are placed in different positions on said carriers to correspond with switch-guides at different stations along the line, so that the carriers may be switched at the stations to which they belong.

The lever G is provided with a pin G', upon which the gripping-jaws G² are pivotally mounted, and said lever is journaled in suitable lugs G³ on the rear side of the carrier. These jaws G² are each provided with a cam-slot G⁴, (see Fig. 3,) which work upon the stud G⁵, secured to the end of the carrier, and said cam-slots G⁴ are of such form that the jaws will be opened, Figs. 2 and 3, as the lever G is lowered in position to cause the jaws G² to engage with the cable D. When the lever G is released, the spring G⁶, located at the back of the carrier and around the lever G, between the lugs G³, will operate to raise the lever G and close the jaws G² upon the propelling-cable D.

The construction of the jaws above described and the lever for operating the same forms no part of this invention, as it is shown, described, and claimed in United States Letters Patent issued to the Lamson Consolidated Store Service Company, of Newark, New Jersey, as my assignee, on January 5, 1897, and numbered 574,715.

II is a plate secured to the bottom of the carrier by screws II', and said plate is provided with ears II², which are adapted to pass under the rails A' of the track A and hold the carrier thereon, as said ears extend beyond said rails A', excepting where said rails A' are bulged at A² to permit a carrier being placed on said rails.

II³ represents friction-rollers mounted upon the screws II' and free to revolve thereon, and the object of these rolls is to prevent friction when the carrier is traveling along the track, around the corners, and into the stations.

The rails A' are secured to the brace A³, located near the standard B⁶, and to the upper end of said brace A³ there is secured a cam-plate A⁴, pivotally secured to the vertical arm A⁵ of the brace A³ by the pin A⁶. The pin A⁷, secured to the upper end of the arm A⁵, extends through the slot A⁸ and guides said cam-plate A⁴ in its movements, as hereinafter described.

On the pin A⁹, journaled in the bracket A³, is a latch A¹⁰, mounted on said pin and normally in the position shown in Figs. 1 and 2 and connected with the pin A¹¹ on the cam-plate A⁴ by reason of the spring A¹², which is adapted to act on said latch and hold it in the above-described position. Fixed fast on said latch A¹⁰ is a plate A¹³, having a slot A¹⁴, with which the pin G⁷ on the under side of the lever G is adapted to register when the carrier is placed upon its proper track to be returned to the station from which it came.

It will be understood that a number of these lines enter the terminal station, and the operator in returning the carrier should place it upon its proper return-track, when it will go to the station from which it was sent. Now if the cashier at the terminal station places the proper carrier upon the proper track, as illustrated in Figs. 1, 2, and 3, the pin G⁷ will pass through the slot A¹⁴ without affecting the engaging position of the latch A¹⁰ with the pin A¹¹, so that said cam-plate A⁴ is held in the position shown in Figs. 1, 2, and 3, and the lever G, as the carrier is pushed forward by the cashier, is depressed, thereby causing the gripping-jaws G⁵ to move into the position shown in Figs. 2 and 3 around the cable D, and as the lever G passes under the end of the cam-plate A⁴ the jaws G² close upon and grip the cable D by reason of the spring G⁶, and the carrier is propelled to the station from which it came.

Referring now to Figs. 5 and 6, the carrier C (shown in said figures) does not belong on the track on which it has been placed and is pushed by the cashier in the usual manner to the position shown in Fig. 5, and the end of the lever G passes under the cam-plate A⁴. As the pushing on said carrier continues, the pin G⁷, which does not register with the slot A¹⁴, will move the latch A¹⁰ from its engaging position shown in Figs. 1, 2, and 3 to that shown in Fig. 6, and the cam-plate A⁴ moves upwardly, as shown, and the

lever G, moving under said cam-plate, is not depressed, and consequently the jaws G² of the gripping mechanism are not opened and lowered around the cable D in position to grip said cable, but remain closed above the cable, and consequently the carrier does not engage the cable D and is not propelled along the track. The cashier observing that the carrier is not propelled along the track moves it rearwardly, and in said rearward movement the end of the lever G will strike on the rear end A¹⁵ of the cam-plate A⁴, which causes the front end of said cam-plate A⁴ to move downwardly, and as the front end of said cam-plate moves downwardly the latch A¹⁰ moves over the pin A¹¹ and holds said cam-plate in the position shown in Figs. 1, 2, and 3. In this position when the carrier is placed on its own track the gripping mechanism is operated as the pin G⁷ passes through the slot A¹⁴, and the gripping-jaws grip the cable, and the carrier returns to the salesman, from whom it was sent. The guide-rod I serves to steady the carrier as the lever G passes under the cam-plate A⁴. The carriers are sent to the cashier's station from the salesmen's stations on the lower track B, composed of two opposite rails B', and said rails are bulged at B² the same as the track A at A² (see Fig. 1) in order to allow the carriers to be removed, as the distance between the rails B' at B² is greater than the distance between the ears II² of the plate II, secured to the bottom of the carrier. The rods B³, located on opposite sides of the rails B', serve to keep the carriers on the forwarding-track as they pass into the cashier's station.

B⁴ represents a suitable bumper against which the carriers strike when coming in on the forwarding-track B, and B⁵ is a suitable brace connecting the rails B'.

It will be understood that the pins G⁷ and slots A¹⁴ are so arranged that the pin G⁷ on the carriers belonging to a certain track will register with the slot A¹⁴ on the latch A¹⁰ of said track, so that the gripping mechanism of the carriers belonging to a certain track will engage only the cable of said track.

From the above description it will be understood that although several cable-lines, each composed of an upper and lower track and similarly constructed, with the exception of the location of the slot A¹⁴, enter the terminal station from different parts of the store yet by the mechanism above described, even though the carriers become mixed at the terminal station and are placed on the return-track of the wrong line, the gripping mechanism of the carriers wrongly placed will not operate to engage the cable of and be propelled on the wrong track. Consequently the carriers running into the terminal or cashier's station on the several lines can only be propelled on the tracks to which they belong to the station from which they were sent.

I do not limit myself to the arrangement and construction shown, as the same may be

varied without departing from the spirit of my invention.

Having thus ascertained the nature of my invention and set forth a construction embodying the same, what I claim as new, and desire to secure by Letters Patent of the United States, is—

1. In a conveying apparatus, the combination of the tracks and propelling-cable with a terminal station into which said tracks enter, carriers adapted to travel on said tracks each provided with a gripping mechanism for engaging the cable, and grip-operating mechanism on the return-track at said terminal station, the gripping mechanism of the carriers belonging to a certain track and the said grip-operating mechanism being provided with registering parts whereby only carriers belonging to a certain track can grip the cable of said track and be propelled thereon.

2. In a conveying apparatus, the combination of the tracks and propelling-cable with a terminal station into which the tracks enter, carriers adapted to travel on said track and each provided with gripping-jaws for engaging the cable, a lever connected to said gripping-jaws and adapted to operate the same, a grip-operating mechanism consisting of a cam on the return-track at said terminal station for operating said lever, and a device for normally retaining said cam in its operative position, the said lever connected to the gripping-jaws on the carriers belonging to a certain track and the said retaining device being provided with registering parts whereby only carriers belonging to a certain track can grip the cable of said track and be propelled thereon.

3. In a conveying apparatus, the combination of the tracks and propelling-cable with the terminal station into which the tracks enter, carriers adapted to travel on said track and each provided with gripping-jaws for engaging the cable, a lever connected to said gripping-jaws and adapted to operate the same, a grip-operating mechanism consisting of a cam on the return-track at said terminal station for operating said lever, and a latch for normally holding said cam in its operative position, the said lever connected to the gripping-jaws on the carriers belonging to a cer-

tain track and the said latch being provided with registering parts whereby only carriers belonging to a certain track can grip the cable of said track and be propelled thereon.

4. In conveying apparatus, the combination of the tracks and propelling-cable with a terminal station into which the tracks enter, carriers adapted to travel on said track and each provided with gripping-jaws for engaging the cable, a lever connected to said gripping-jaws and adapted to operate the same to actuate the gripping-jaws of the carriers to bring said gripping-jaws into position to grip the cable and provided with a projecting pin, a grip-operating mechanism consisting of a cam on the return-track at said terminal for operating said lever, a latch for normally holding said cam in its operating position and provided with a slot through which the said pin passes to cause the engagement of the gripping-jaws and the cable, and mechanism located on the carriers for causing the said gripping-jaws to grip the cable, the said pin on the carriers belonging to a certain track being adapted to register with the slot of the latch of said track, whereby only the carriers belonging to a certain track can grip the cable of said track and be propelled thereon.

5. In a conveying apparatus, the combination of the tracks and propelling-cable with a terminal station into which said tracks enter, carriers adapted to travel on said tracks each provided with a gripping mechanism for engaging the cable, grip-operating mechanism on the return-track at said terminal station, and means on each return-track for holding said grip-operating mechanism in position to operate said gripping mechanism on the carriers and adapted when actuated by the movement of a carrier placed on the wrong return-track to release said grip-operating mechanism and thereby prevent the engagement of the gripping mechanism on the carrier with the propelling-cable of said track.

In testimony whereof I have signed my name to this specification, in the presence of two subscribing witnesses, this 8th day of February, 1898.

JAMES T. COWLEY.
